UNITED STATES PATENT OFFICE.

HENRY S. CROOKE AND LEWIS CROOKE, OF NEW YORK, N. Y.

COMBINED FOIL AND PAPER FABRIC.

SPECIFICATION forming part of Letters Patent No. 289,505, dated December 4, 1883.

Application filed November 3, 1883. (No model.)

To all whom it may concern.

Be it known that we, HENRY S. CROOKE and LEWIS CROOKE, citizens of the United States, residing in the city of New York, county of New York, and State of New York, have invented certain new and useful Improvements in Combined Foil and Paper Fabrics, fully described and represented in the following specification and the accompanying drawings, forming a part of the same.

In order to render the highly-ornamental tin-foil of commerce capable of use for inclosing and covering articles of manufacture and goods put up in small packages, it has long been the practice to protect it from rupture, and the articles and goods it covers from injury, by combining with it a lining of paper, which latter was depended upon for the necessary strength to retain the foil in place and resist any tendency to tearing, rupture, or abrasion likely to result in ordinary use, thus enabling this foil, capable of receiving beautiful surface-finish, to come largely into use wherever its water-repellent or ornamental qualities were desirable. This method of protection was improved by the discovery of a means of uniting the thin foil—whether plain, embossed, printed, frosted, rendered dead-white, or otherwise ornamented—directly with the paper backing, so that the two became a compound or united fabric. Such a fabric has become a product largely used, especially where strips of it require to be attached to goods, or sheets of it are formed into envelopes that require frequent opening. Practically it has been found, however, that where raw edges of this compound or united fabric are exposed, especially when cut into narrow strips—now largely used as bands upon plugs of tobacco and similar packages—the abrasion due to handling causes the united layers to separate at the extreme edges, which separation, once started, is liable to extend to such a degree as to destroy the strip.

It is the object of the present improvement to remove this defect; and the invention consists in providing a sheet or strip of compound foil and paper, whether united by cement or paste or not, with a folded edge which may extend along the two sides of the strip only, or also be provided at the ends. Many forms

of the fold may be made, and accordingly the drawings illustrate several.

Figure 1 shows a strip or sheet composed of a thin foil layer, 2, laid upon a layer of paper, 3, as is common. Fig. 2 illustrates by a perspective view, and Fig. 3 by a cross-section, (enlarged,) such a strip having its sides protected and made strong by folding the compound layers of foil 2 and paper 3 upon themselves, so that while the main or central portion, B, of the strip is composed of two layers, the edges A are composed of four layers—two of foil and two of paper. (See Fig. 3.) In this embodiment of the invention the central portion, B, is also depressed, so that the edges A project upward, while the paper layer throughout the central portion, B, is on a level with the under surface of each edge. In Fig. 4 a strip like that shown in Fig. 1 has its extreme ends turned over and folded. In Fig. 5 the combined layers have their edges folded so that the entire face-surface body B and edges A lie in the same plane, which, of course, causes the doubled edges to project from the back side of the strip. In Fig. 6 the two layers of foil and paper laid together, as in Fig. 1, have their edges folded upward, thus presenting a face surface the body B of which presents the foil 2, while the edges A present paper surfaces. In Fig. 7 the paper under strip or lining is shown as narrower than the face layer or covering of foil, the edge A being produced by folding the foil over the paper, as is shown in Fig. 8, and though in this latter figure the upsetting of the edges A is such as to present the depressed center B, a level center, as in Fig. 5, may be had, if desired. Where the paper is cut away, the edges will be less cumbersome than the other structures having one less thickness of paper.

A practical mode of making these strips with folded or bound edges is had by uniting or associating the two materials in large sheets superposed, then cutting the same into strips of appropriate size, and then, by means of any common folding devices, the edges, to a proper width, are gradually turned up and over onto the body, or vice versa, and then pressed down into place. Properly-furrowed rolls will cause the body of the strip to be pressed downward, so that the back surface

will be level and the edges protrude on the face side, or vice versa.

It is preferable that the foil shall be embossed to heighten its ornamental effect, and this should be done by passing the combined material between properly-engraved rollers, whereby they are perfectly laid together and given even surfaces.

Where the paper lining is made of a single layer and the foil layer is wrapped over it, the paper and foil of appropriate widths must, of course, be united in narrow widths. The layers may be cemented together or not, as may be preferred, though in most uses of the combined fabric this is desirable.

Strips made according to this invention present what may be termed "bound edges" that will resist all ordinary wear and use, and their layers have no tendency to separate. They are especially well adapted to be handled in the speedy manipulation required in applying them to packages, as they afford a greater rigidity than can be attained by the union of their layers in any other way. In the special use of such strips in the marking of plugs of tobacco, (the strip bearing the graduations for division of the plugs, or trade-marks and the like,) the element of great strength is very desirable, as the strips, after being applied to the plugs, are subjected, when a mass of the plugs are packed together in a box, to very great pressure, and when plug after plug is removed from the box the foil surface of these

strips will resist all tendency to be pulled off from the paper lining or the whole strip from the plug, which is one of the defects found in the old form of foil strip.

The form of strip having a depressed center is especially desirable, for the reason that its protruding edges A present a comparatively small surface-area to be engaged by a foreign body, and its tender foil surface is thus largely protected, and particularly is this so when the turned-over portion presents a face of paper.

Cloth—such as buckram, sleazy muslin, and like cheap fabrics—whether stiffened or not with sizing, may be substituted for paper, and are therefore to be considered an equivalent thereof.

What is claimed is—

1. A strip or sheet formed from a compound fabric of tin-foil and paper, provided with folded edges, substantially as described.

2. A strip or sheet consisting of a layer of foil and a layer of paper, provided with folded edges and having its central part depressed, substantially as described.

In testimony whereof we have hereunto set our hands in the presence of two subscribing witnesses.

HENRY S. CROOKE.
LEWIS CROOKE.
